UNITED STATES PATENT OFFICE

VICTOR MARKKULA, OF ABERDEEN, WASHINGTON

HOSE REEL AND DRIER

Application filed February 25, 1931. Serial No. 518,269.

This invention relates to the class of winding and reeling and pertains particularly to improvements in hose reels.

The primary object of the present invention is to provide a hose reel of such a character that the hose will be drained of water as it is wound up on the reel, the wound up hose forming a vertical spiral when completely rotated on the carrier.

10 Another object of the invention is to provide a vertical reel upon which the hose is wound, in association with which a vertically movable guide operates, which supports the hose at the proper level as it is reeled up.

15 Still another object of the invention is to provide a reel upon a wheeled carrier, with gear means connecting the reel with the wheels of the carrier whereby the reel may be positively rotated as the carrier is moved over the ground, the gear mechanism being adjustable or shiftable so that the direction of rotation of the reel may be controlled or the reel may be completely disengaged from the wheels so as to freely rotate, or the gear mechanism may be so locked that rotation of the reel or of the carrier wheels is prevented.

20 Other objects and advantages of the present invention will become apparent as the description proceeds and the invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as 25 expressed in the appended claims.

In the drawings:

Figure 1 is a view in side elevation of the hose reel and drier or drainer embodying the present invention;

45 Figure 2 is a vertical transverse sectional view taken on the line 2—2 of Figure 1;

Figure 3 is a bottom plan view of the same, parts thereof being in section;

50 Figure 4 is a horizontal sectional view taken on the line 4—4 of Figure 1;

Figure 5 is a sectional view taken on the line 5—5 of Figure 4;

55 Figure 6 is a view in top plan of a cross bar of the carrier with which the gear control levers are connected.

Referring now more particularly to the drawings wherein like numerals of reference indicate corresponding parts throughout the several views, the numeral 1 indicates generally the carrier of the present hose reel structure which as shown comprises a pair of side beams 2 arranged in spaced relation and upon which is mounted, at the forward ends thereof, the platform 3.

60 The forward ends of the beams 2 have extending thereacross an axle 4, the ends of which have bearings in the beams and extend beyond the outer sides thereof as shown in Figure 3. Upon each outer end of the axle 4 there is mounted a wheel 5. Either or both of the wheels 5 may be secured to the axle to turn the same therewith.

65 Extending transversely beneath the platform 3 at a point rearwardly of the axle 4 and spaced from the under side of the platform is a beam 5' and further to the rear there extends between and connects the beam 2, a second beam 6. The rear ends of the beams 2 are of a suitable size and shape to provide handles 7, by means of which the carrier may be moved in the same manner as a wheel barrow. Supporting legs or feet 8 are attached to the under surfaces of the beams 2, one at each side thereof and adjacent the cross beam 6 as shown in Figure 3.

70 Mounted in a suitable bearing 9 located upon the longitudinal center of the platform 3 and directly above the axle 4, is a vertical shaft 10, the upper end of which extends through and rotates in an aperture in the horizontal plate or bar 11 which forms the top of a frame structure which is indicated generally by the numeral 12. This bar or plate 11 extends longitudinally of the carrier and is connected at its forward end with a pair of upright bars 13 which form one side of the frame and at its rear end with a similar pair of upright bars 14 which form the rear side of the frame, the lower ends of these bars 13 and 14 being turned at right angles 75

as indicated at 15 to form feet which rest upon and are secured to platform 3.

The vertical shaft 10 supports a reel cylinder which is indicated generally by the numeral 16. This cylinder consists of the upper and lower discs 17 and 18 respectively, the peripheries of which are connected by the vertical bars 19. Wound about the reel is a spiral hose support indicated generally by

- 10 the numeral 20, this support being of angular cross section and having one flange thereof extending outwardly and at a slight upward inclination from the bars 19 as indicated at 21 while the other flange extends downwardly and outwardly from the bars as indicated at 22 thus forming a space between the convolutions of the spiral in which a hose body may position in the manner shown, the hose upon the reel being indicated generally by the numeral 23. At the bottom of the reel there is mounted a spring clip 24 with which one end of the hose 23 may be engaged and a similar clip 25 is mounted at the top of the reel for securing the other end of the hose thereto after it is completely wound thereon.

Mounted for vertical movement upon the upright bars 13 of the frame, is a plate 26 from which there projects inwardly the flange 27, the free edge of which is arcuately formed as indicated at 28 to conform with the curvature of the spiral hose guide, over the flange 21 of which it engages as shown in Figure 4. At one side the flange 27 carries a tubular guide 29 through which the hose 23 passes as it is wound on the reel, as illustrated in Figure 1, the outer end of this tubular guide having a roller 30 in the lower part thereof over which the hose passes.

The upper end of the shaft 10 carries a hand crank 31 by means of which the reel may be manually rotated if desired.

Adjacent the lower end the shaft 10 has secured thereto the bevel gear 32 which is designed to be engaged by one or both of the two gears 33 which are keyed to the axle 4. As illustrated in Figure 2, the platform 3 is provided with suitable apertures 34 through which the gears 33 may project for engagement with the gear 32.

Extending beneath the platform is a pair of levers each of which is indicated by the numeral 35, each of these levers passing over the beam 5' and having pivotal connection therewith as indicated at 36. The forward end of each lever carries a pair of spaced apertured fingers 37 through which the shaft 4 passes and between which a gear 33 is located. The rear ends of the levers 35 extend over the top of the cross beam 6 of the structure and this beam is provided at each side of the transverse center with a pair of notches 38 in one of which the end of the adjacent lever 35 engages.

From the foregoing description it will be readily seen that in order to wind up a hose

upon the reel 16 the end of the hose must first be passed through the guide tube 29 of the shiftable member 26 and attached to the lower clip or hook 24. In order to reel the hose up by pulling the carrier away from the hose, assuming that the same is placed in a coil upon the ground, the right hand lever is located in the outside one of the pair of notches at the right of the carrier and the left hand lever is placed in the inner one of the notches at the left hand of the carrier.

Should the hose be lying straight out upon the ground it may be reeled up by pushing the carrier from one end thereof to the other, after running one end of the hose through the guide 29 and attaching it to the hook 24 as previously described and then shifting the levers 35 so that the left hand one will lie in the outer end of the two notches adjacent thereto and the right lever will lie in the inner one of the two notches adjacent thereto. By placing both levers in the inner ones of the notches both gears 33 will be disengaged from the gear 32 and the carrier may be shifted forwardly or backwardly without turning the reel and if the levers are both shifted so as to engage in the outer ones of the notches 38 both gears 33 will be connected with the center gear 32 and the wheel and reel may be locked together so that the carrier cannot move.

Having thus described my invention what I claim is:—

1. A hose reel of the character described comprising a wheeled platform including an axle, a vertical shaft rotatably mounted on the platform, means connecting said vertical shaft with said axle to transmit motion therefrom to the shaft, a reel carried by the shaft, a hose guide arranged spirally about said reel and formed from a member of angular cross section, one flange thereof being extended laterally from the reel and the other flange extending downwardly along the side thereof, the convolutions of said guide being spaced to permit the positioning of a hose between the lateral flange of one convolution and the downwardly extending flange of another convolution, and a vertically movable member having engagement with the lateral flange of the spiral guide and formed to provide a guide tube through which a hose may pass to the reel.

2. A structure of the character described comprising a platform, supporting means for said platform including an axle rotatably connected therewith and wheel members carrying said axle, a vertically disposed shaft mounted at its lower end in a bearing upon the platform, a reel carried by said shaft and comprising an upper and lower disk-like element and spaced bar members disposed about and connecting the edges of said disks, an element formed of two angularly disposed flanges disposed to extend spirally about said

reel from the top to the bottom thereof, one flange of the element extending outwardly and at an upward inclination from the side of the reel and the other flange having its 5 lower edge turned outwardly from the reel and spaced a sufficient distance from the outwardly directed flange of the next lower convolution to receive a hose body, means for effecting the rotation of the reel from said 10 axle, and a vertically movable hose guide designed to move longitudinally of the reel with a hose as the latter is wound thereon.

3. A structure of the character described, 15 comprising a platform, supporting means for said platform including an axle rotatably connected therewith and wheel members carrying said axle, a vertically disposed shaft mounted at its lower end upon the platform,

a vertically disposed cylindrical body mounted on and having the shaft extending axially therethrough, an element formed of two angularly disposed flanges, extending spirally about said cylindrical body from the top to the bottom thereof, one flange of the element extending outwardly and at an upward inclination from the side of the body and the other flange having its lower edge turned outwardly from the body and spaced a sufficient distance from the outwardly directed flange of the next lower convolution to receive a hose body, means for effecting the rotation of the body from said axle, and a vertically movable hose guide designed to move longitudinally of the body with the hose as the latter is wound thereon.
